UNITED STATES PATENT OFFICE.

EDOUARD DESCOMPS, OF UTICA, NEW YORK, ASSIGNOR OF ONE-HALF TO
LOUIS LOMBARD, OF SAME PLACE.

CAR-REPLACER.

SPECIFICATION forming part of Letters Patent No. 448,137, dated March 10, 1891.

Application filed December 3, 1890. Serial No. 373,397. (No model.)

To all whom it may concern:

Be it known that I, EDOUARD DESCOMPS, a citizen of the Republic of France, and a resident of Utica, in the county of Oneida, in the 5 State of New York, have invented new and useful Improvements in Derailed-Car Replacer, of which the following, taken in connection with the accompanying drawings, is a full, clear, and exact description.

10 The purpose of this invention is to provide simple, convenient, and efficient means for expeditiously replacing on the track-rails a car which has been thrown from said rail; and to that end the invention consists, essentially, of a shoe formed at its bottom with a seat, by which it is adapted to rest on the track-rail, and is also formed at its top with a seat for the reception of the end of the car-replacing rail, all as hereinafter more fully 15 described, and specifically set forth in the 20 claims.

In the annexed drawings, Figure 1 is a plan view of a section of track-rail, with my improved car-replacer applied to said rail. Fig. 25 2 is an enlarged side view of the same, with the track-rail shown in dotted lines. Fig. 3 is an end view of the car-replacing shoe mounted on the track-rail. Fig. 4 is a detached perspective view of the component parts of the 30 car-replacer. Fig. 5 is an inverted plan view of the shoe, and Fig. 6 is a transverse section of a modification of my car-replacer.

Similar letters of reference indicate corresponding parts.

35 R represents the stationary track-rail.

A denotes the shoe hereinbefore referred to, which shoe is formed with a suitable bearing a , preferably convexed longitudinally and adapted to rest upon the track-rail R, as 40 shown. To retain the said shoe on the track-rail I form the under side of the shoe with a downwardly-projecting shoulder a' , which abuts with its side against the usual vertical offset o of the rail, and thus prevents the shoe 45 from slipping from one side of the rail R. The slipping of the shoe from the opposite side of the rail is prevented by a chain f , attached at one end to the side of the shoe and secured at the opposite end to an anchoring 50 pin or spike passing through a ring r on the

chain and driven into the ground at a point in a line at right angles to the side of the shoe, as illustrated in Fig. 1 of the drawings. Another chain f' is attached to the shoe, and in securing the shoe to the rail R this latter 55 chain is extended rearward from the shoe, and a pin or spike is inserted in a ring on the end of said chain and driven into the ground. This latter arrangement anchors the shoe so as to prevent it from slipping longitudinally 60 on the track-rail. To allow the said shoe to be placed diagonally on the rail R, I form the shoulder a' diagonally across the bottom of the shoe, as shown more clearly in Fig. 5 of the drawings. The rear portion of the top of 65 the shoe I form with a bearing for the end of the car-replacing rail r , which bearing I prefer to form of mortises $p p$ and an intermediate tongue t , and an upward-projecting transverse shoulder e in front of said mortises. 70

The end of the rail r is formed with downward-projecting lugs $l l$ and intermediate notch n , and is placed with said lugs in the mortises $p p$ of the shoe, and is thus prevented from slipping either laterally or longitudinally on the shoe. The notch n , being 75 over the tongue t , is filled by a key d , inserted in the notch and resting on the tongue.

Both ends of the rail r may be formed with the lugs $l l$ and intervening notch n , so that 80 either end of said rail may be connected to the shoe A. Furthermore, in some cases the shoulder a' on the bottom of the shoe may be dispensed with, as represented in Fig. 6 of the drawings.

In replacing a derailed car the shoe is placed in its requisite position upon the track-rail and securely anchored, as hereinbefore described, and then the free end of the rail is placed in front of the derailed car-wheel. 90 The car being then moved toward the rail r , it is caused to mount said rail, and is thereby guided onto the shoe A, from which it passes onto the track-rail.

Having described my invention, what I 95 claim as new, and desire to secure by Letters Patent, is—

1. In a car-replacer, the replacing-rail r , in combination with the shoe A, formed with a bearing for the end of said rail and having 100

- its bottom formed with the downwardly-projecting shoulder a' , substantially as and for the purpose set forth.
2. In a car-replacer, the combination of the shoe A, formed with the mortises $p p$ in its top, and the rail r , provided at its end with the lugs ll , entering said mortises, as set forth.
3. In combination with the shoe A, formed with the mortises $p p$, and intermediate tongue t , the rail r , formed with the lugs ll and intermediate notch n , and the key d , entering said notch, as set forth and shown.
4. A car-replacer consisting of the shoe A, formed at its under side with the shoulder a' , extending diagonally across it, and provided at its top with the mortises $p p$ and intermediate tongue t , and upward-projecting shoulder e , the rail r , formed with the lugs ll and intermediate notch n , and the key d , entering said notch, substantially as described and shown.
5. The combination, with the shoe A and rail r connected thereto, of the chain f , attached to the said shoe and provided with a ring for the reception of an anchoring-pin, as set forth.
6. The combination, with the shoe A and rail r connected thereto, of the lateral anchoring-chain f and longitudinal anchoring-chain f' , attached to the shoe, and each of said chains provided with an eye for the reception of an anchoring-pin, substantially as described and shown.

In testimony whereof I have hereunto signed my name this 22d day of November, 35 1890.

EDOUARD DESCOMPS. [L. S.]
